UNITED STATES PATENT OFFICE.

CLARENCE DARRELL, OF FLATTS, BERMUDA.

DESIGN FOR A BICYCLE-PUMP.

SPECIFICATION forming part of Design No. 29,577, dated November 1, 1898.

Application filed September 27, 1898. Serial No. 692,028. Term of patent 7 years.

To all whom it may concern:

Be it known that I, CLARENCE DARRELL, a subject of the Queen of England, residing at Flatts, Bermuda, have invented and produced a certain new and useful Design for a Bicycle-Pump; and I do declare the following to be a full, clear, and exact description of the invention, such as will enable others skilled in the art to which it appertains to make and use the same, reference being had to the accompanying drawing, and to the letters of reference marked thereon, which forms a part of this specification.

This invention relates to a certain new and useful design for bicycle-pumps.

The design embodying my invention is clearly illustrated in the accompanying drawing, which, with the letters of reference marked thereon, forms a part of this specification, and in which drawing I have shown a perspective view of a bicycle-pump constructed in accordance with my design.

Reference being had to the details of the drawing by letter, A designates the body portion of the pump, which is of elliptical form 25 and terminates at its ends in disks E and F, which disks have milled peripheries. The disk E has on its outer face a short cylindrical extension E', while the disk F has a tubular extension C, which terminates in a screw-threaded end and has adjacent to the threads a disk with milled periphery, as illustrated.

Having thus described my design, what I claim as new, and desire to secure by Letters Patent, is—

The herein-described design for a bicycle-pump, substantially as shown and described.

In testimony whereof I affix my signature in presence of two witnesses.

CLARENCE DARRELL.
